SHOE MACHINE

Walter P. Osgood, Malden, Mass.

Application May 24, 1937, Serial No. 144,428

14 Claims. (Cl. 12—51)

The present invention relates to machines which are used in the manufacture of shoes to apply pressure progressively to a seam ridge formed in joining a plurality of sheets or upper blanks, such as a pair of quarters, by a seam. This operation is known in the shoe industry as the seam pressing operation, the purpose of which is to press the upstanding seam ridge beyond its elastic limit to set it in a permanently deformed condition in a single plane thus to render the seam ridge innocuous to the strains to which it is subjected during the various shoe-making operations and to provide for a straight, good-looking seam crease in the finished shoe. In some cases the application of progressive pressure is accompanied by the application of tape to the seam ridge and to the inside faces of the quarters at opposite sides thereof. It must be understood, however, that with respect to tape-severing certain features of the present invention are useful when embodied in machines for applying tape to a single sheet or upper blank as well as in machines for applying tape to and adjacent a seam ridge.

The work is presented to a seam pressing machine for the seam-pressing operation in a turned inside-out condition thus to develop an upstanding seam ridge. For a long time it has been highly desirable in the shoe industry that the machine, during the seam-pressing operation, turn the quarters right side out. It has been proposed heretofore to obtain this desirable result by providing the work-supporting roll with a peripheral groove as disclosed by me in my Patent No. 19,319, reissued September 18, 1934. Experience has demonstrated that with a work-supporting roll having a peripheral groove, the work is reversed only if the operative uses her hand as a guide to control the shape of the work as it leaves the seam pressing machine.

The principal object of the present invention is to produce a seam-pressing machine which will perform the seam-pressing operation in a satisfactory manner and deliver positively the finished work in a right side-out condition.

Further objects of the present invention are to simplify and improve the work support and the mechanism for simultaneously operating the tape guide and actuating the tape-severing knife to sever the tape.

To the accomplishment of these objects the various features of the present invention reside in certain devices, combinations and arrangements of parts hereinafter described and then pointed out in detail in the appended claims,

possessing advantages readily apparent to those skilled in the art.

Figure 1 is a view, partly in section, in left side elevation;

Fig. 2 is a view, partly in section, of the work-supporting structure;

Fig. 3 is a detail view in front sectional elevation of the first work-supporting roll;

Fig. 4 is a detail view in front sectional elevation of the second work-supporting roll;

Fig. 5 is a view in front sectional elevation, parts of the frame being broken away for convenience;

Fig. 6 is a detail view in front sectional elevation of the presser foot supporting structure;

Fig. 7 is an enlarged detail view in left side elevation;

Fig. 8 is a view in sectional plan on the line 8—8, Fig. 7;

Fig. 9 is a detail view in right side elevation of the tape-severing knife cam and the button for engaging it at the will of the operative;

Fig. 10 is a detail view in plan of a modified form of work support;

Fig. 11 is a detail view in left side elevation of the work support illustrated in Fig. 10;

Fig. 12 is a detail view in right side elevation, partly in section;

Fig. 13 is a view in sectional plan on the line 13—13, Fig. 1;

Fig. 14 is a view in sectional plan on the line 14—14, Fig. 2, and

Fig. 15 is a detail view in plan of the work support illustrated in Figs. 1, 2, 3 and 4.

The work is supported for the combined tape-applying and seam-pressing operation by two rolls 16 and 17, (Fig. 1), arranged in line in the direction of feed indicated by the arrow therein, the roll 16 first engaging the leading edge of the work and the roll 17 last engaging the trailing edge of the work.

The roll 16, (Fig. 3), comprises a metal shell 18, the work-engaging periphery of which is provided with a central flat land 19 flanked by beveled lands 20 and 21. The shell 18 is provided with flanges 22 which embrace the side faces of a rubber ring 23 upon which the shell 18 is mounted. The ring 23 is mounted upon a sleeve 24, the opposite ends of which engage the inside faces of the arms of a yoke 25 secured to the upper end of a spindle 26, (Fig. 2). The sleeve 24 is mounted to rotate freely upon a stud 27 secured to the arms of the yoke 25 and bridging the space between them.

The roll 17 comprises a rubber ring 28, (Fig. 55

4), mounted in a channel 29 formed in the periphery of a metal ring 30 rotatably mounted upon a stud 31 secured to the arms of the yoke 25.

The spindle 26, (Fig. 2), is mounted to slide vertically but held from rotation in a post 32. To this end the spindle 26 is provided with a narrow key 35 which rides in an elongated slot 36 formed in the post 32. The bottom of the spindle 26 is threaded to receive the threaded upper end of a rod 37, the lower end of which supports a closed link 38 to which a treadle-connected rod 39 is hooked.

Near its lower end the rod 37 is threaded to receive a nut 40 provided with a circular series of openings 41, (Figs. 2 and 14), one of which is adapted to receive loosely a pin 42 carried by the lower end of a sleeve 43. The upper end of the sleeve 43 through which the rod 37 passes loosely is threaded into the lower end of the post 32. As shown in Fig. 2 the central portion of the bottom of the sleeve 43 is provided with a cylindrical seat 44 in which the central portion of the top of the nut 40 is seated, there being a washer 45 interposed between the nut 40 and the sleeve 43. The nut 40 and sleeve 43 are held in contact and the work-supporting rolls 16 and 17 are projected yieldingly from the upper portion of the post 32 by a spring 46 housed in the lower end of the post, coiled about the rod 37 and interposed between the bottom of the spindle 26 and the top of the sleeve 43.

With this construction the work support may be lowered against the tension of the spring 46 by depression of the treadle-connected rod 39. During this movement the nut 40 is separated from the sleeve 43 but the amount of separation is not sufficient to cause the opening 41, which receives the pin 42 to clear it. When the treadle-connected rod 39 is released the spring 46 re-stores the work-supporting rolls and the nut 40 to their normal operating positions.

The lower portion of the rod 37 is threaded into the nut 40. These threads have the same pitch as the threads by means of which the sleeve 43 is threaded into the post 32. With this construction rotation of the nut 40 and sleeve 43 as a unit results in the variation of the tension of the spring 46 without, however, varying the operating position of the work-supporting rolls.

To vary the operating height of the work-supporting rolls without variation in the tension of the spring 46 the pin 42 is withdrawn from the nut 40, which is then rotated on the sleeve 43 in the desired direction and to the desired extent, the pin 42 being then replaced in the sleeve 43 and inserted in one of the other openings 41 in the nut 40.

Broadly considered the post 32 may be rigidly supported from the frame of the machine when the work-supporting rolls are embodied in a top-taping machine or in a back-seam machine in which the quarters operated upon are not fitted in a closed upper. In order, however, that after each successive operation on the back seams of uppers each closed in a ring-like form, the operative may allow the upper, respectively, to drop down over the post 32 and accumulate in a stack thereon, the post 32 is pivoted so that it may be swung from the full line position of Fig. 1 to the construction line position and thus facilitate the removal of the stack.

The stack of closed uppers to be operated upon may be placed over the post 32 while in the construction line position of Fig. 1 and the uppers withdrawn therefrom, one at a time, while the

work-supporting rolls are in the full line position of Fig. 1 in which case the hammer to be described will feed the upper so withdrawn out of the machine.

The post 32, near its base, is provided with an arm 47, (Fig. 13), having lateral bosses 48 thereon, the end face of each of which is centrally recessed to receive the conical ends of screws 49 carried by a dome 50, on the machine frame, both the dome and the frame having openings 51 through which the post 32 works.

The post 32 is held in the full line position of Fig. 1 by a latch 52 having a beveled face 53 which engages a similar face 54 formed on the bottom of an ear 55 on the post 32. The post 32 is prevented from excessive movement to the left, (Fig. 1), by a pair of stop screws 56 carried by the dome 50 and arranged, respectively, to engage projections 57 on the post 32.

The latch 52 is slidably mounted in a guideway 58 formed in an extension 59 of the dome 50. The latch 52 is connected to one end of a rod 60, the other end of which is provided with a handle 61 by means of which the latch 52 may be withdrawn from the ear 55 to permit the post 32 to fall into the construction line position of Fig. 1 under the influence of gravity. A second rod 62 connected to the handle 61 is received within an opening 63 formed in the extension 59 to prevent rotation of the latch.

When the handle 61 is released the latch 52 is projected into the position of Fig. 1 by a spring 64 housed in the extension 59 coiled about the rod 60 and interposed between the latch 52 and the closed end of the guideway 58. When the operative pushes the post 32 from the construction line position of Fig. 1 to the full line position thereof the latch 52 is wedged into the guideway 58 against the tension of the spring 64 by a cam surface 65 formed on the ear 55.

Associated with the work-supporting rolls is a seam-crease guide 66, (Fig. 1). The seam ridge is guided by a guide 67 having a construction and mode of operation substantially like the leather seam-ridge guide disclosed in my Patent No. 1,850,120, March 22, 1932. The guide 67 is connected detachably to a bracket 68, (Figs. 1, 5 and 7). The bracket 68 is secured to a block 69 which is supported from a bracket 70 secured to the machine frame.

After the work has been placed in position on the work-supporting rolls with the seam-crease and the seam-ridge engaged by their respective guides, the tape is applied to the work by a seam-pressing hammer 71, (Fig. 7), carried by a lever 72. The head 72 is formed with a slot 73, (Figs. 1 and 7), in which is received slidably a block 74 that is pivoted at 75 to the machine frame. The upper end of the lever 72 is connected to an eccentric (not shown) on the drive shaft 76, (Fig. 1). As disclosed more fully in my Patent No. 1,646,212, this construction reciprocates the hammer 71, to press the seam-ridge progressively and apply tape thereto, and oscillates the hammer 71 in contact with the work, to impart thereto a feeding movement. During this feeding movement the hammer 71 draws tape through a tape guide 77, (Figs. 1 and 7), from a suitable source of supply extending in the machine from a coil, (not shown), to the tape guide. Intermediate the coil and the tape guide the machine is provided with a tape pull-off mechanism having substantially the same construction and mode of operation as the corresponding pull-off disclosed in my Patent No. 1,899,051, February 28, 1933.

The tape guide 77 and its associated tape-stripping plate 78 have a construction and mode of operation with respect to tape-guiding and tape-stripping substantially like the corresponding parts disclosed in my Patent No. 2,026,911, January 7, 1936. The tape guide 77 is supported from one end of a rock shaft 79 journaled in the block 69. The other end of the rock shaft 79 is provided with an arm 80, the free end of which is connected by a link 81 to the lower end of an arm 82 depending from a rock shaft 83 journaled in the machine frame. The rock shaft 83 is provided with a second arm 84, the free end of which is pivoted to the upper end of a treadle-connected rod 85, a spring, (not shown), being connected thereto in the usual manner to return the parts to normal position after the depressed treadle has been released by the operative.

The normal position of the tape guide is illustrated in Fig. 7. In this position the tape guide cooperates with the hammer 71 below the path of operation of the tape-severing knife 86. The tape-severing knife 86 comprises a plate 87, (Fig. 8), provided with a salient cutting edge 88. The plate 87 is secured to a holder 89, (Fig. 7), projecting laterally from one end of an arm 90, the other end of which is secured to one end of a rock shaft 91 journaled in the block 69. The other end of the rock shaft 91 is provided with a cam plate 92 which may be engaged by a button 93 rotatably mounted on one end of a horizontal rod 94 slidably mounted in a sleeve 940 threaded into the reciprocating and oscillating head 72. The button 93 is maintained normally at one side of the vertical plane of the cam plate 92 by a spring 95, coiled about the rod 94 and interposed between the button 93 and the adjacent end of the sleeve 940. The spring 95 moves the button 93 and the rod 94 to the right, viewing Fig. 5, until stopped by the nut 96 on the opposite end of the rod. The button 93 is pressed to the left, viewing Fig. 5, against the tension of the spring 95 by a cam block 97 adjustably secured to the link 81. The tape-severing knife is maintained normally in the position of Fig. 7 by a coiled spring 98, one end of which is connected to the block 69 and the other end of which is connected to the arm 90. Movement of the tape-severing knife in the other direction is limited by a pin 99 projecting from the block 69.

Thus, through the connections described the tape-severing knife is maintained normally in an inoperative position and the tape guide 77 is maintained normally in a position below the path of operation of the tape-severing knife, in which position the tape guide cooperates with the hammer 71.

When the treadle-connected rod 85 is depressed by the operative the tape guide 77 is swung upwardly to a position above the path of operation of the tape-severing knife, in which position the tape guide cooperates with the knife, and the button 93 is forced by the cam block 97 into the vertical plane of the cam plate 92 so that the tape-severing knife is operated to sever the tape by the same power driven mechanism which reciprocates and oscillates the seam-pressing and tape-applying hammer 71. The tape-severing knife is operated to sever the tape on one of the downward movements of the head 72. The tape-severing knife is retracted after its tape-severing movement by the coiled spring 98, a forwardly projecting ledge 100 on the block 69 limiting the movement of the arm 90 under the influence of the spring 98. The cam block 97 is mounted adjustably upon the link 81 to facilitate providing

for the time of operation of the tape-severing knife relative to the time of operation of the tape guide from its position below the path of operation of the tape-severing knife to its position above that path, the desideratum being to cause the knife in its tape-severing stroke to clear the bottom of the tape guide during its upward swinging movement and to provide the tape with a dangling cut end so that the tape presenter 78 may pick it up and pull the tape into the line of feed when the tape guide is restored to its normal operating position.

The operative inserts the work in the machine being careful to engage the seam crease with the seam crease guide 66 and the seam ridge with the seam ridge guide 67, the work being turned inside out to develop the upstanding seam ridge. The operative then feeds the work in the direction of the arrow, (Figs. 1 and 7), to bring the leading edge of the work into the zone of activity of the hammer 71 thereby picking up the leading edge of the freshly cut tape and interposing it between the hammer 71 and the top of the seam ridge.

The toe 102 of the hammer 71 cooperates with the downgoing side of the roll 16 to apply the tape to the seam ridge and to perform thereupon that operation known in the shoe industry as the seam-pressing operation. The heel 103 of the hammer 71 cooperates with the upgoing side of the roll 17 to apply the tape to the face of the quarters at opposite sides of the taped and pressed seam ridge. During this operation the surface 28 on the roll 17 yields to permit the taped and pressed seam ridge to pass between the heel 103 and the roll 17 without injury.

The toe 102 of the hammer 71 feeds the leading edge of the work progressively down the downgoing side of the roll 16 until the leading edge engages a bite guard 104, (Fig. 7), which prevents the leading edge of the work from passing down between the rolls 16 and 17 and deflects the leading edge of the work upwardly into engagement with the upgoing side of the roll 17. During the time the work is bridged across the rolls 16 and 17, the work is acted upon by the shank 105 of the hammer 71 which imparts to the seam ridge face of the work a concave curvature both along the length of the seam ridge and across the quarters laterally thereof. Thus, the hammer 71 in cooperation with the rolls 16 and 17 applies tape to the seam ridge, presses the taped seam ridge, applies tape to the faces of the quarters at opposite sides of the taped and pressed seam ridge, imparts a shape to the quarters which they assume when assembled upon the heel end of a last, and irons the seam crease side of the quarters to impart a finished appearance thereto free from the undesirable "crow's-feet."

In order to aid the hammer 71 in concaving the seam ridge face of the work and to insure the setting of the quarters in the position they assume when assembled upon the heel end of a last, the opposite sides of the arms of the yoke 25 are provided, respectively, with wings 106 and 107 which engage the finished faces of the quarters and support them while the hammer 71 operates upon the unsupported seam ridge portion of the work.

Each wing is provided with a shank 108, (Fig. 1), secured by screws to an arm of the yoke 25, a flaring quarter-engaging edge 109, (Fig. 15), and an undercut portion 110, which permits that portion of the flaring edge 109 first to be engaged by the quarter to be located over the top

of the arm of the yoke 25 close to the side of the roll 16.

As indicated in Fig. 5 the quarter-engaging edges of the wings 106 and 107 flare outwardly for most of their lengths, the edges flaring inwardly adjacent their rear ends. For some classes of work it may be desirable to provide the reversing wings with quarter-engaging edges 111 and 112 which flare outwardly for a portion of their lengths, flare inwardly for another portion and flare outwardly again adjacent their rear ends.

During the action of the hammer 71 upon that portion of the work which extends unsupported between the rolls 16 and 17 and between the reversing wings 106 and 107, the taped and pressed seam ridge is engaged by a presser foot 113, (Fig. 7), in order to resist the tendency of the work to spring upwardly during the idle stroke of the hammer. The presser foot 113 is formed upon the lower end of a lever 114 which works in a slot 115, (Fig. 6), formed through the central portion of the hammer, and which is pivoted upon a pin 116 secured to a presser foot support 117. The upper end of the support 117 is provided with a post 118 which is secured to a carrier 119 having a rod 120, (Fig. 6), which passes through the slot 73 in the hammer head 72 in position to be secured to the frame of the machine as by a nut and washer fastening 121.

The pin 116, upon which the presser foot lever 114 is pivoted, is provided with an arm 122 having a hooked end 123 which hooks over the shank of a screw 124, the head of which clamps the arm 122 to the support 117.

The presser foot 113 is urged into engagement with the taped and pressed seam ridge by a coiled spring 125, one end of which is hooked through an eye 126 formed in the lever 114 and the other end of which is hooked over a pin 127 projecting forward from the carrier 119.

Nothing herein explained is to be interpreted as limiting the various features of the present invention in the scope of its application to use in connection with the particular machine or the particular mode of operation or any combination thereof selected for purposes of illustration and explanation. While the particulars of construction herein set forth are well suited to one mechanical form of the invention and to the uses to which it is put, it is not limited as to these uses, nor to these details of construction, nor to the conjoint use of all its features, nor is it to be understood that these particulars are essential since they may be modified within the skill of the artisan without departing from the true scope of the actual invention, characterizing features of which are set forth in the following claims by the intentional use of generic terms and expressions inclusive of various modifications.

What is claimed as new is:

1. A seam-pressing machine having, in combination, means for supporting the work comprising a pair of spaced apart rolls, a bite guard interposed therebetween, means constructed and arranged to bridge the space between the rolls over the bite guard and bend the flesh or unfinished face of the work about an axis extending substantially normal to the line of feed, and a seam ridge presser foot.

2. A seam-pressing machine having, in combination, means for supporting the work comprising a pair of spaced apart rolls, means constructed and arranged to bridge the space between the rolls and bend the flesh or unfinished

face of the work about an axis extending substantially normal to the line of feed, and means flanking the rolls for supporting portions of the work unsupported thereby.

3. A seam-pressing machine having, in combination, means for supporting the work comprising a pair of spaced apart rolls, means constructed and arranged to bridge the space between the rolls and bend the flesh or unfinished face of the work about an axis extending substantially normal to the line of feed, means flanking the rolls for supporting portions of the work unsupported thereby, and a seam ridge presser foot.

4. A seam-pressing machine having, in combination, means for supporting the work comprising a pair of spaced apart rolls, and a combined tape-applying and seam-pressing means constructed, arranged and operated to cooperate first with one of the rolls only to press the seam ridge, apply tape thereto and feed the work, then with both rolls to bend the work about an axis extending substantially normal to the line of feed, and finally with the other one of the rolls only to apply tape to the work at opposite sides of the taped and pressed seam ridge and to feed the work out of the machine.

5. A machine for applying pressure progressively along a work piece having, in combination, a work support, means cooperating therewith to press a work piece inserted therebetween, a spring for moving the work support in one direction, a treadle-controlled means for moving the work support in the other direction, means for varying the tension of the spring without varying the relation of the work support to the pressing means and means for varying the relation of the work support to the pressing means.

6. A machine for applying pressure progressively along a work piece having, in combination, a work support, means cooperating therewith to press a work piece inserted therebetween, a spindle upon which the work support is mounted, a pivoted post in which the spindle is movable vertically, a sleeve threaded into the post, a nut engaged with the sleeve, a treadle-connected rod threaded into the nut and connected to the spindle, a spring housed in the post coiled about the rod and interposed between the spindle and the sleeve, and a connection between the sleeve and the nut permitting a relative movement therebetween.

7. A machine for applying pressure progressively along a work piece having, in combination, a spindle upon which the work support is mounted, a pivotal post in which the spindle is movable vertically, a sleeve threaded into the post, a nut engaged with the sleeve, a treadle-connected rod threaded into the nut and connected to the spindle, a spring housed in the post coiled about the rod and interposed between the spindle and the sleeve, and a connection between the sleeve and the nut permitting a relative movement therebetween either of separation or rotation.

8. A machine for applying pressure progressively along a work piece having, in combination, a work support, means cooperating therewith to press a work piece inserted therebetween, a spindle upon which the work support is mounted, a pivoted post, a key and slot connection between the spindle and the post, a sleeve threaded into the post, a nut, having a series of openings, engaged with the sleeve, a treadle-connected rod threaded into the nut and connected to the spindle, a spring housed in the post coiled about

the rod and interposed between the spindle and the sleeve, and a pin carried loosely by the sleeve adapted to engage loosely the selected one in the series of nut openings.

5 9. A machine for applying pressure progressively along a work piece having, in combination, a work support, means cooperating therewith to press a work piece inserted therebetween, a treadle-connected spindle upon which the work 10 support is mounted, and a post, pivoted about a horizontal axis, within which the spindle is movable longitudinally.

10 10. A machine for applying pressure progressively along a work piece having, in combination, 15 a work support, means cooperating therewith to press a work piece inserted therebetween, a treadle-connected spindle upon which the work support is mounted, a pivoted post within which the spindle is movable longitudinally, and means 20 for latching the post from movement under the influence of gravity.

11. A machine for applying pressure progressively along a work piece having, in combination, a work support, means cooperating therewith to 25 press a work piece inserted therebetween, a treadle-connected spindle upon which the work support is mounted, a pivoted post within which the spindle is movable longitudinally, means for latching the post from movement under the influence of gravity, comprising a latch and an 30 ear on the post, a spring for inserting the latch beneath the ear, a cam surface on the ear for operating the latch against the tension of the spring, and manual means for withdrawing the 35 latch from beneath the ear.

12. A tape-applying machine having, in combination, tape-applying means, power-operated mechanism for operating the tape-applying means including a button, a tape-severing device, a rock shaft upon which the tape-severing device is mounted having a cam normally opera-

tively disconnected from the button, a tape guide normally occupying a position below the path of operation of the tape-severing device, and means for operatively connecting the button and the cam and for locating the tape guide above 5 the path of operation of the tape-severing device comprising an arm connected to the tape guide rock shaft, a treadle-connected arm and a link connecting the arms having a cam arranged to engage the button. 10

13. A tape-applying machine having, in combination, tape-applying means, power-operated mechanism for operating the tape-applying means, including a button, a tape-severing device, a rock shaft upon which the tape-severing device is mounted, having a cam normally operatively disconnected from the button, a tape guide normally occupying a position below the path of operation of the tape-severing device, and means for operatively connecting the button 15 and the cam and for locating the tape guide above the path of operation of the tape-severing device comprising an arm connected to the tape guide rock shaft, a treadle-connected arm and a link connecting the arms, said link having a 20 cam adjustably mounted thereon and arranged to engage the button. 25

14. A machine for applying pressure progressively along a work piece having, in combination, a work support, means co-operating therewith to 30 press a work piece inserted therebetween, a spindle upon which the work support is mounted, a post in which the spindle is movable vertically, a sleeve threaded into the post, a nut engaged with the sleeve, a treadle-connected rod 35 threaded into the nut and connected to the spindle and a spring housed in the post, coiled about the rod and interposed between the spindle and the sleeve, the threads on the sleeve and the rod having the same pitch. 40

WALTER P. OSGOOD.
